UNITED STATES PATENT OFFICE.

THOMAS JAMES, JR., OF PHILADELPHIA, PENNSYLVANIA.

LOCOMOTIVE VALVE-GEAR.

1,226,523.

Specification of Letters Patent.

Patented May 15, 1917.

Application filed February 21, 1917. Serial No. 150,101.

To all whom it may concern:

Be it known that I, THOMAS JAMES, Jr., a citizen of the United States, residing at 403 Belmont Apartment, Thirty-fourth and Spring Garden streets, Philadelphia, in the county of Philadelphia and State of Pennsylvania, have invented new and useful Improvements in Locomotive Valve-Gears, of which the following is a specification.

10 This invention relates to improvements in valve gears, and has particular reference to a valve gear for use in connection with the usual reciprocating piston valves of the type now commonly employed in locomotive engines.

One of the main objects of the invention resides in a valve gear of peculiar construction and operation for effecting the operating movements of a steam distribution valve 20 of a locomotive engine, said gear being adapted to operate the valve to effect an accelerated opening and closing of the steam ports governed thereby, and at the same time to permit of an extended open period of said 25 ports, in order that a prolonged expansion of steam, admitted by said ports into a cylinder, will be obtained, together with greatly decreased exhaust compression.

Another important object of the invention 30 resides in providing a valve gear having adjustable features of construction which will permit the lap and lead movements of the steam distribution valve to be readily controlled, thus permitting the engine, with 35 which the valve gear is associated, to be readily and easily started in a gradual manner, and without unnatural jolting or jarring.

A further object of the invention resides 40 in a valve gear possessing the above characteristics, which will be positive and efficient in operation, not liable to become out of order or adjustment, and to permit the engine associated therewith to be more economically 45 operated.

Other objects will be in part obvious and in part pointed out hereinafter.

To this and other useful ends, the invention consists of features hereinafter set forth 50 and claimed.

In the accompanying drawings—

Figure 1 is a diagrammatic side elevation of the valve gear embracing the principles of the present invention, the same being 55 shown as applied to a locomotive steam engine, parts of the latter being broken away

to disclose the underlying construction, the valve gear being shown in a neutral or out of gear position.

Fig. 2 is a similar view showing the valve gear, disclosing the same in its extreme forward position.

Fig. 3 is a transverse vertical section taken along the line 3—3 of Fig. 1.

Fig. 4 is a horizontal sectional view taken along the line 4—4 of Fig. 1.

Fig. 5 is a similar view, the plane of which being disclosed by the line 5—5 of Fig. 1.

Fig. 6 is an enlarged horizontal sectional view taken through a portion of the mechanism disclosed in Fig. 5.

Fig. 7 is a detail vertical sectional view taken through a portion of the mechanism disclosed in Fig. 5.

Fig. 8 is a diagrammatic view illustrating the relative positions of the distribution valve, radius rod, combination lever, and the co-operating crosshead, when the latter is moving in the direction of the arrow, and 80

Fig. 9 is a similar view disclosing the positions of the parts enumerated in Fig. 8 when the crosshead is reciprocating in the opposite direction.

Similar characters of reference denote 85 corresponding parts throughout the several figures of the drawings.

Referring to the drawings by numerals, the valve gear comprising the present invention, is shown as employed in connection with a locomotive engine 1, consisting of a cylinder 2, piston 3, steam-distribution valve 4, and steam ports 5. The valve 4 in this instance is of the usual piston valve type, and is constructed to permit of "inside admission" of steam into the cylinder 2. The piston 3 is connected by means of a piston rod 6 to a sliding crosshead 7, mounted in fixed guides 8, and a pitman rod 9 is pivotally connected with the crosshead, and is swiveled as at 10 to one of the driving wheels 11 of the locomotive. A return crank 12 rotatable with the wheel 11, has pivotally connected to the outer end thereof an eccentric rod 105 13, the latter leading to an oscillating reverse link 14, pivotally mounted upon the frame 16 of the locomotive. A radius rod 17 has one extremity thereof slidably mounted within the link, and is adjustable 110 in the latter so as to regulate the operation of the valve 4, whereby the forward, rear-

ward or neutral positions of the valve gear may be controlled. To adjust the rod within the link, a bell crank 18 is provided, said crank having one of the arms thereof mov- 5 ably connected with one end of the radius rod, and the other end connected with a manually controlled rod 19, whereby the said end of the radius rod may be adjusted to different positions within said reverse 10 link. The above parts are of the usual construction in operation, therefore, a more extended explanation relative thereto will be omitted.

Secured in any simple manner to the 15 crosshead 7 is a plate 20, the latter being provided with an extended bifurcated extremity 21 in which is secured, by mechanism to be hereinafter fully described, the lower extremity of a combination "lap and 20 lead" and cut off lever 22. The latter extends upwardly to a position substantially in axial alinement with the valve 4, and is connected with said valve through the provision of an elongated slot 23, formed in 25 the lever 22. Mounted in the slot is a reciprocating block 24, through which a pin 25 passes, the latter having its extremities fixed in the bifurcated end 26 of a sliding crosshead 27, which is mounted in fixed 30 guides protruding from the casing of the engine 1. The crosshead 27 is suitably connected with the outer end of a valve stem 28, extending from the distribution valve 4, in order that the reciprocating movements 35 of the crosshead 27 will be synchronously imparted to said valve. It will be noted that the lower end of the lever 22, where it is connected with the plate 20, will move on a plane parallel to the direction of movement of the crosshead 7, and by the use of the slot and block connection 23 and 24, a peculiar movement will be imparted to the valve 4 so as to effect the above stated objects. The outer end of the radius rod 17 40 is pivotally connected with the upper extremity of the lever 22, at a point above the block 24, said rod, in this instance, being employed to regulate the distance between the pin 25 and the point of pivotal connection between the rod 16 and the combination lever 22, whereby the out of gear or in gear positions of the valve gear will be obtainable.

At this juncture attention is directed to 55 the diagrammatic views illustrated in Figs. 8 and 9 of the drawings, which plainly disclose the movements of the distribution valve 4, when the crosshead 7 is moving in the directions indicated by the arrows. In 60 these views the line A represents the direction of travel of the valve, the line B the movement of the crosshead, and the obliquely directed line C the various positions the lever 22 will assume when in operation, 65 the upper ends of the line C indicate the

curve or path of travel of the forward extremity of the radius rod 17. Thus in Fig. 8, where the line C' intersects the line A, the valve 4 will be in a "line and line" position closing the ports 5, but when the cross-head travels a relatively short distance to the position indicated by the line C², the valve 4 will be quickly reciprocated to effect a complete opening of the port, so that the cylinder 2 will receive an unobstructed flow 70 of steam, and to simultaneously permit of a full and free exhaust of the spent steam on the opposite side of the piston, as will be clearly understood. The ports will then remain open until the lever 22 is substantially past its center of travel, that is, until it arrives at the position indicated by the line C³, this being accomplished by reason of the peculiar method of mounting the lever 22, whereby the supply of steam will be cut off in relatively the same accelerated manner as was effected during the opening of the ports. The advantages derived by reason of this substantially rapid, or intermittent movements of the valve, together 80 with the prolonged opening of the ports 5, may be briefly stated as follows: firstly, the quick admission of steam into the cylinder, effected from the rapid opening of the ports; secondly, the prolonged period of 85 steam expansion; thirdly, the extended open position of the ports when steam is being exhausted therethrough, so as to eliminate the back pressure upon the piston. 90

Coöoperating with the valve reciprocating 100 mechanism, above described, is a variable lead controlling device for regulating the admission of steam into the cylinder 2. As is well known, in the ordinary "Walschaert" valve the "lead" remains constant, which is 105 exceedingly objectionable when the engine is being initially started, this being due to the fact that steam is admitted into the cylinder an instant before the piston reaches the extremity of its stroke, thus causing a 110 back pressure upon the slowly moving piston, which is a distinct detriment to the successful start of the engine. However, the constant lead operates very efficaciously 115 when the engine is running at full speed. For example, this action may be likened to the operation of an internal combustion motor, when first started the "spark" for effecting the explosions of the mixture within its cylinders is retarded, so that the explosion will not take place until the piston is on a down stroke. But after the engine gathers momentum the spark is advanced until the explosions created thereby occur just before the piston reaches the end of 120 its up-strokes. Therefore, the variable lead device utilized by the present invention, presents means for regulating the movement of the valve 4 so that when the engine 1 is being initially started, steam will be admitted 125

into the cylinder immediately subsequent to the period when the piston reaches the extremity of its movement. And further provides manually controlled means for shifting the valve, after the starting of the engine, so that the admission of steam into its cylinders will take place just before said piston arrives at its stroke extremities.

To effect this object the lower end of the lever 22 is provided with a circular opening in which is positioned an eccentric 30, the latter being provided with a squared opening for the reception of a similarly shaped portion 31 of a shaft 32, which is journaled for rotation in the bifurcated end 21 of the plate 20. A crank 33 is secured to one end of the shaft 32, and has its free extremity pivotally connected with a link 34, the other end of said link being jointed as at 35 to a cooperating link 36 pivotally carried by the plate 20. Connected with the links 34 and 36 is a variable lead arm 37, the latter extending parallel with the lever 22, and has its upper end swiveled to the radius rod 17, at a position contiguous to the joint existing between said rod and the lever 22. It will be noted by reference to Figs. 1 and 2 that the combination lever and the arm 37 will extend in parallel relation; regardless 30 of the position of the crosshead, this being due to the block and slot connection utilized in associating said lever with the crosshead 27.

In conclusion, it is obvious that when the radius bar 17 is shifted to vary the cut-off, the link 27 pulls the eccentric 30 by means of its connection therewith to cause the combination lever 22 to be raised in order that the lead will be progressively increased with 40 the cut-off. It is due to the adjustment of the rod 17 which causes the lead to change, the lead remaining constant after the adjustment is made.

From the foregoing it will be seen that there is provided mechanism through which the objects of the invention have been achieved, and that all of the advantageous features above mentioned are, among others, present. The gear described may be readily 50 attached, if desirable, upon any locomotive embracing the sliding piston valve construction, with but a minimum of cost and diffi-

culty. The construction of the gear, by reason of its simplified nature, will enable the same to be absolutely reliable in operation, 55 and not likely to become out of order, or to require constant attention and adjustment. Moreover, the invention does not employ any extra levers to enable the engineer of a locomotive to regulate its several positions, 60 but is automatically operated by the usual reverse lever, common to all locomotives.

Having described the invention what is claimed as new and patentable is:

1. In valve gear of the class described, 65 the combination with an engine including a reciprocating piston valve and crosshead, a plate secured to the crosshead, articulated links pivotally connected with said plate, an eccentric carried by the latter and having 70 the positions thereof regulated by said links, of a lap and lead lever having the substantially lower extremities thereof provided with an opening for the reception of said eccentric, whereby said lever will be capable 75 of moving in unison with said crosshead, a radius rod connected with the upper extremity of said lever, a stem protruding from the valve and having a block and slot connection with said lever, and a variable 80 lead controlling arm connected with said radius rod and with said links at a position contiguous to said lever and adapted to maintain substantially parallel relation with the latter, irrespective of the positions of 85 said crosshead.

2. In valve gear of the class described, the combination with a locomotive steam engine including a reciprocating crosshead and a steam-distribution valve, a plate secured to 90 said crosshead, an eccentric carried by said plate, a lap and lead lever connected with said eccentric, a pin and slot connection provided contiguous to the upper extremity of said lever, and having connections with said 95 distribution valve, a radius rod pivoted to said lever at a position above said pin and slot connection, and a variable lead arm connected with said radius rod and with said eccentric, and operable to regulate the 100 substantially vertical positions of said lever.

In testimony whereof I affix my signature.

THOMAS JAMES, JR.
